UNITED STATES PATENT OFFICE.

ANDREW KERR, OF BELFAST, IRELAND.

AUTOMATIC EMERGENCY CONTROL APPARATUS FOR STOP-VALVES.

1,184,350.

Specification of Letters Patent.

Patented May 23, 1916.

Application filed April 11, 1913. Serial No. 760,342.

To all whom it may concern:

Be it known that I, ANDREW KERR, a subject of the King of Great Britain, residing at Belfast, Ireland, have invented certain 5 new and useful Automatic Emergency Control Apparatus for Stop-Valves, of which the following is a specification.

This invention relates to marine and land power plant installations and has for its 10 object to provide improved automatic explosion and emergency control mechanism for closing the stop valve or valves.

Under my invention I provide hydraulically operated apparatus for automatically closing boiler and engine stop valve or valves in the event of a burst in the pipe lines or in the event of the steam in any other way accidentally escaping and causing a reduction 15 in pressure in the steam pipes, the apparatus being also adapted, when required, to act as an emergency hand control mechanism for the stop valves so that they may be controlled from any desired points in a ship, and in the case of land work so that they 20 may be controlled from different positions in a factory or other place being supplied with power from a power station.

In order that my invention may be clearly understood I have hereunto appended an explanatory sheet of drawings whereon my invention is shown by way of illustration.

Figure 1 is a view showing the arrangement diagrammatically, and Fig. 2 is a view of a detail hereinafter referred to.

35 The portion to the left of the dotted line A. B. Fig. 1 applies to both marine and land work and the portion to the right thereof applies to land work only. The relative positions and proportions of the different 40 parts of the apparatus may not be as shown, as the grouping and proportions have been adopted for convenience in illustrating the invention.

On the drawings the same reference letters 45 wherever repeated indicate the same or similar parts.

a is a boiler, b a boiler stop valve, c an engine stop valve.

c¹ is a steam pipe leading from the boiler 50 stop valve b to the engine stop valve c.

The control apparatus in accordance with my invention for both marine and land work comprises water tanks d and e, the tank d being placed at a suitable height above the 55 level of the cylinder i to insure the pipe lines h and n remaining full of water, the tank d

being also a suitable distance below the level of the tank e and both tanks placed in a convenient position, the tank e being preferably in the boiler room and the tank d preferably 60 in the engine room and conveniently situated in the engine room I provide a hydraulic cylinder f and to the rear of the piston f¹ therein a supply of water under pressure is provided by means of a pipe line g carried 65 up to a suitable height to obtain the desired head of water, the water being obtained by condensing steam in a coil g² the steam being obtained from the engine stop valve c, through a cock g³ which is capable of being 70 locked open, and pipe g¹ to the coil g². The top g⁴ of the coil g² must be disposed at such a height above the water level X. X. in the boiler a as will give a pressure in excess to the working drop in the pipe g. A supply 75 of water at boiler pressure is led from the water space in the boiler by the pipes h⁰ and h¹ to the front of the piston f¹ in the cylinder f, the water being supplied to the pipe h⁰ through a non-return valve h² in the wa- 80 ter space of the boiler, said valve h² being adapted to be locked in the open position. The piston f¹ is connected with and adapted to operate a valve k of convenient form 85 which controls communication between the pipe h⁰ and the pipe line h leading to the top of a cylinder i. The cylinder i is conveniently supported close to the stop valve b, the piston i¹ in the cylinder i being connect- 90 ed by a rod i² with levers j fulcrumed at j¹ on the rod j² conveniently supported near the stop valve b. The lever j is also pivotally connected at j³ with the valve spindle b¹, of the stop valve b the connection being made to crosshead j⁴ having part j⁵ project- 95 ing into a socket j⁶ in the screwed spindle j⁷ connected to the handle j⁸, the arrangement being such that the levers j can operate the valve spindle b¹ independently of the hand gear j⁸ and when required the latter is also 100 instantly ready for use. A pipe line l leads from the bottom of the tank e to the rear of the piston i¹ in the cylinder i. The slide valve k controls a port m¹ into a cylinder m in which a piston valve m² (with holes there- 105 in to allow water to pass to either side there- of and place the piston in equilibrium) is provided under control of a hand lever m⁴. The piston valve m² is normally open as shown in the drawings and is held in open 110 position by the catch m⁵ engaging in a notch in a quadrant m⁶, so that when the valve k

uncovers the port m^1 as hereinafter explained there is clear passage for the water from the boiler through the port m^1 , cylinder m , port m^2 to the pipe line h . From 5 the pipe line h a pipe n leads to one end of a non-return valve o and from the other end of said valve a pipe line p leads to the tank d , the pipe p being preferably led into the tank d as shown at p^1 to prevent grit 10 and dirt entering the pipe line p , the other water pipes being similarly led into their respective tanks. The valve o is normally held open by gravity or gravity assisted by a light spring, and it is shut by boiler pressure 15 in the pipe n when the valve h is opened as hereinafter described, and it may be opened by hand when desired by means of the lever o^1 when the valve m^3 is shut and so relieve the pressure on the top of the 20 piston i^1 and allow the difference in head of water between tanks d and e to raise the piston i^1 for the purpose of opening the valve b , assisted by the steam pressure behind same.

25 The pipe line g in a marine installation would preferably be carried along the tunnels, around the stoke hold, alley ways, captain's room and elsewhere as desired and any required number of cocks g^5 provided 30 therein to act as emergency control valves so that as hereinafter explained the stop valves may be shut down by means of any of the cocks g^5 , which would be inclosed in boxes with instructions on outside of box.

35 The cock g^7 is provided in the pipe line g at or near the engine room and it is intended mainly for shutting down the valve b hydraulically by hand when required. In order to prevent the possibility of the cock 40 g^7 being left open to atmosphere when the valve b is opened again, I provide a link g^8 connected at one end g^9 through the medium of a slot g^{10} and a pin with the hand lever m^4 and at its other end g^{11} it is connected to a lever g^{12} for operating the cock 45 g^7 , the arrangement being such that when the valve b is opened as hereinafter described the moving over of the lever m^4 automatically closes the cock g^7 to the 50 atmosphere so that the pipe line g will be again ready for the restoration of the pressure head of water behind the piston f^1 , thus placing the apparatus again in condition for action when required. As the head of 55 water in the pipe line g requires to be such as will give a pressure in excess of the working drop, *i.e.* the drop in pressure which may take place due to any usual racing of the engines, I preferably provide means for 60 adjusting the head of water in the pipe line g . The adjusting means may take the form shown at Fig. 1 of the drawings where it will be seen that the portion g^0 , g^1 is slidably carried within the lower portion 65 of the pipe g . An alternative method of

adjusting the length of the pipe g , g^0 , g^1 is shown at Fig. 2 in which case it will be observed that the pipe g^0 can be readily pulled out or pushed in to give the desired head.

70 For land work I provide an emergency apparatus comprising auxiliary tanks r and s to contain some suitable non-freezing fluid. The tank r is placed at a suitable height above the tank s and I provide a cylinder t 75 and from the tank r a pipe line u leads to the rear of a piston t^1 in the cylinder t while a pipe line v leads from the tank s to the front of the piston t^1 . The piston t^1 is connected by a rod t^2 with a valve t^3 80 inserted between the pipe line g and the cylinder f , and controlling a port f^2 leading into the cylinder f from the valve casing t^4 and capable of putting the port f^2 in communication with a port f^3 leading to atmosphere. 85

I preferably lead the pipe line u around the various rooms or workshops and, if necessary, near to individual machines and I provide any number of cocks u^1 in said pipe line whereby it can be put into instant communication with atmosphere so that the pressure in the pipe line is relieved and the piston t^1 operated so as to close the stop valve b as hereinafter explained and, 90 if desired, as an additional safeguard, I may simultaneously operate a brake w^1 in connection with the fly-wheel w of the engine. For this purpose I provide a cylinder z with a piston z^1 therein and lead a branch pipe v^1 from the pipe line v to the rear of said piston and I also lead a branch pipe line n^1 from the pipe h to the front of the piston z^1 . To enable one size of cylinder z 95 to be used for varying requirements as regards the load, I provide adjusting means z^2 on the rod z^3 whereby the load on the brake block may be controlled or adjusted. 100

In operation the tanks e and d are supplied with water by any ordinary automatic supply arrangement; the non-return valve h^2 is opened and locked in the open position; the pipe h^0 between the cock h^2 and the valve casing h^1 is filled with water; the pipe h^1 from the pipe h^0 to the port f^4 and the part of the cylinder f in front of the piston f^1 are also filled with water. The pipe line l from the tank e is filled with water and the portion of the cylinder i behind the piston i^1 is also filled with water and the pipe line h from the valve m to the front of the piston i^1 is also filled with water, the pipe lines n and p being also filled. The steam cock g^3 is then opened and locked in the open position so that steam from the pipe line g^1 passes to the coil g^4 where it is 115 condensed and fills the pipe g , valve casing t^4 , and the portion of the cylinder f behind the piston f^1 , the valve m^3 being in the open position as shown, and held in the open position 120 as shown, and held in the open position 125 as shown, and held in the open position 130

tion by means of the catch m^5 and notch m^7 , and the valve o is also held open by the action of gravity, assisted if desired, by a spring or springs. The apparatus does not in any way interfere with the closing or opening of the stop valves b by the ordinary hand gear and the valve b can be closed by screwing down the spindle j^1 as usual. The screwing down of the valve b by hand gear is a gradual movement and the consequent pressure on the piston i^1 causes the water in the pipe line l to be displaced into the tank e and a corresponding movement of water from the tank d and pipe line p through pipe line h to the front of the piston i^1 and vice versa when the valve b is opened by the hand gear.

In the drawings the various parts of the apparatus are shown in the position they occupy under normal working conditions with the stop valve b open. When a burst takes place in the pipe line c^1 or when from any other cause the pressure in the pipe line is reduced below the working drop then the pressure in the pipe line g will be correspondingly reduced so that the pressure at the rear of the piston f^1 in the cylinder f will also be reduced and when this occurs the pressure of water in the pipe line h^1 which is at boiler pressure will force over the piston f^1 causing it to move the valve h so as to open the port m^1 and allow water to pass freely at boiler pressure from the pipe h^0 through the valve cylinder m and as the pressure of water closes the valve o the water passes to the pipe line h and from thence to the top of the piston i^1 in the cylinder i , forcing same downward against the head of water in the pipe l . The movement of the piston i^1 acts on the levers j and causes a corresponding downward movement of the spindle b^1 to close the valve b and thereby shut off the steam supply at the boiler a . The pipe line h may of course connect to any desired number of cylinders i to operate same and to close a corresponding number of stop valves. When the necessary repairs have been effected the pressure can be taken off the top of the piston i^1 by closing the port m^2 through the medium of the cut off valve m^3 , by means of the hand lever m^4 , then by opening the valve o by hand the water will be free to pass from the pipe line h to the pipe line p and owing to the steam pressure on the bottom of the stop valve b it will be raised with the assistance of the head of water in the pipe line l and the piston i^1 will be forced up and the water in the pipe line h displaced into the tank d until the piston i^1 reaches the top of its stroke at which position the stop valve b will be full open. When the valve b has been opened the pressure in the pipe line g will be restored by the passage of steam through the cock g^3 so that when the valve o is re-

leased the excess of pressure in the pipe line g will move over the piston f^1 and automatically open the valve m^3 by the action of the stopper f^5 against the hand lever m^4 which is slidably fulcrumed at m^8 so that the apparatus is again in the position shown in the drawing and ready for the next breakdown. The valve o can be used to open the valve b to any required amount by simply holding down the lever o^1 and opening the valve o against the water pressure in pipe n and thereby opening the valve b as desired and then releasing the lever o^1 when the required opening of valve b is effected; valve o will then be closed again by the water pressure in the pipe n . The opening of the valve o connects the pipe lines h and p and the greater head in pipe line l then forces the piston i^1 upward and so opens the valve b as required. The valve b may be shut again by opening any of the cocks g^5 to atmosphere and relieving the pressure behind piston f^1 as before described. Operation of the valve b as above described could be used as an emergency control for the engines in the event of a breakdown of the engine stop valve or valves. In case of any emergency in which it may be necessary to shut off steam in the tunnels or at the captain's room or elsewhere this can be done by turning any of the cocks g^5 to put the pipe line g in communication with atmosphere which of course would immediately relieve the pressure behind the piston f^1 and so close the stop valve b in the manner already described.

The auxiliary apparatus to the right of the dotted line A. B. is intended mainly for land work and by opening any of the valves or cocks u^1 the pipe line u can be placed in communication with atmosphere and the pressure behind the piston t^1 relieved so that the pressure in front of same obtained from the head of water from the tank s moves the piston t^1 over and causes it to move the valve t^3 thereby putting the port f^2 into communication with the port f^3 which leads to atmosphere and so relieving the pressure behind the piston f^1 so that it is moved in the manner hereinbefore described to close the stop valve b . At the same time the opening of the valve h will place the front of the piston z^1 in communication with a supply of water at boiler pressure and will thereby force the piston z^1 to the rear of its cylinder z and displace the water in the pipe line v into the tank s . This movement of the piston z^1 will act on the lever w^0 in such a way as to cause the brake block w^1 to bear against the fly wheel w of the engine and bring it quickly to rest. The emergency apparatus to the right of the dotted line A. B. may also, when required, be adapted to control the supply of working fluid or fuel or motive power to

steam, gas, oil, or other engines or motors and to stop same in case of emergency. If desired, I may provide a pressure gage α on the pipe line n whereby at any time the pressure in the pipe line h can be ascertained. This will indicate if the valves b are full open by registering the normal working pressure in pipe line n . An air cock i^3 is preferably provided at the top of 10 the cylinder i for the escape of the air when the pipe lines h , p , are being filled with water and similarly an air cock g^1 is preferably provided at the top of the pipe g^1 for the escape of air when the pipe is filling 15 after being connected up.

Having now fully described my invention, what I claim and desire to secure by Letters Patent is:-

1. The combination with a steam generator having a steam supply pipe in communication with the steam space thereof, and a stop valve in the pipe, of an emergency control apparatus comprising, a cylinder connected with the generator and supply pipe, 25 a piston in said cylinder interposed between said connections, a vessel containing fluid at a pressure lower than that within the generator, a valve casing connected with the pressure generator, a valve in said casing connected with said piston, a second cylinder connected with said valve casing and with said vessel, a second piston in said second cylinder connected with the stop valve and interposed between said connections, means 30 whereby when the pressure in the supply pipe falls below that in the generator the movement of the first piston occasioned thereby operates said valve in its casing and connects the second cylinder with the generator thereby causing said second piston to close the stop valve and means whereby said valve may be operated to cut off the supply of pressure fluid from the generator to the second cylinder and thereby allow the pressure fluid from said vessel to act upon the 45 second piston and cause same to re-open the stop valve.

2. The combination with a steam generator having a steam supply pipe in communication with the steam space thereof, and a stop valve in the pipe, of a hydraulically operated emergency control apparatus comprising, a cylinder, a piston therein, connection between the water space of the generator and the cylinder on one side of the piston, connection between the steam supply pipe and the cylinder on the other side of the piston, means inserted in the second mentioned connection to condense steam 50 from the steam supply pipe and allow the water of condensation to exert a pressure in the cylinder normally in excess of the water pressure therein on the other side of the piston, and means adapted to be set in

operation by the movement of the piston 65 occasioned by a fall of pressure in the steam pipe below the pressure in the generator to effect the closure of the stop valve.

3. The combination with a steam generator having a steam supply pipe in communication with the steam space thereof, and a stop valve in the pipe, of a hydraulically operated emergency control apparatus comprising, a cylinder, a piston therein, connection between the water space of the generator and the cylinder on one side of the piston, connection between the steam supply pipe and the cylinder on the other side of the piston, means inserted in the second mentioned connection to condense steam 70 from the steam supply pipe and allow the water of condensation to exert a pressure in the cylinder normally in excess of the water pressure therein on the other side of the piston said means being capable of adjustment to vary the level of water of condensation and the pressure in the cylinder caused thereby, and means adapted to be set in operation by the movement of the piston 75 occasioned by a fall of pressure in the steam pipe below the pressure in the generator to effect the closure of the stop valve.

4. The combination with a steam generator having a steam supply pipe in communication with the steam space thereof, and a stop valve in the pipe, of a hydraulically operated emergency control apparatus comprising, a cylinder, a piston therein, connection between the water space of the generator and the cylinder on one side of the piston, connection between the steam supply pipe and the cylinder on the other side of the piston, means inserted in the second mentioned connection to condense steam 80 from the steam supply pipe and allow the water of condensation to exert a pressure in the cylinder normally in excess of the water pressure therein on the other side of the piston, means whereby the pressure created by 85 the water of condensation can be adjusted, a vessel containing water having a pressure head less than the pressure within the generator, a second vessel containing water having a pressure head less than the head 90 of water within the first vessel, a second cylinder, a second piston therein and connected with the stop valve, means connecting the second cylinder with both water vessels so that the difference in pressures therein maintains the stop valve normally open 95 and whereby when the pressure in the supply pipe falls below the pressure in the generator the movement of the first piston occasioned thereby causes the water supply 100 from the second water vessel to the second cylinder to be cut off and a connection made 105 between the generator and the second cyl- 110

inder, thereby overcoming the water pressure of the first water vessel and causing the second piston to close the stop valve.

5. The combination with a steam generator having a steam supply pipe in communication with the steam space thereof, and a stop valve in the pipe of an emergency control apparatus comprising, a cylinder connected with the generator, an auxiliary 10 valve device connected with the cylinder, the supply pipe and the atmosphere and normally adapted to connect the cylinder with the supply pipe, a piston in said cylinder interposed between said generator and 15 valve device connections, means whereby when the pressure in the supply falls below the pressure in the generator the movement of the piston occasioned thereby causes the stop valve to cut off the steam supply to 20 the supply pipe, an auxiliary cylinder, a piston in said cylinder connected with the auxiliary valve device, two water tanks hav-

ing different pressure heads and connected one to each end of the auxiliary cylinder so as to maintain the piston therein normally 25 in a position to maintain a connection between the cylinder and the supply pipe and means whereby the end of the auxiliary cylinder normally connected with the water tank having the higher pressure head may 30 be placed in communication with the atmosphere thereby causing the piston therein to be moved and operate the auxiliary valve device to close the connection between the cylinder and the supply pipe and open the 35 cylinder supply pipe connection to the atmosphere.

In testimony whereof I affix my signature in presence of two witnesses.

ANDREW KERR.
